UNITED STATES PATENT OFFICE.

AUGUST DIETRICH, OF COLUMBUS, NEBRASKA.

PLATE-GLASS CARRIER.

1,215,350.

Specification of Letters Patent. Patented Feb. 13, 1917.

Application filed February 23, 1916. Serial No. 79,917.

To all whom it may concern:

Be it known that I, AUGUST DIETRICH, a citizen of the United States, residing at Columbus, in the county of Platte and State of Nebraska, have invented a new and useful Improvement in Plate-Glass Carriers, of which the following is a specification.

This invention relates to devices for lifting and carrying plate glass and other bodies having thin, flat surfaces, and it has for its object to provide a device of this kind which is simple in construction and at the same time reliable in operation, that is, sure in its grip upon the smooth faces of the 15 glass or other body, so that there is no danger of breakage or injury to the operator or to the article being carried.

The invention will be first hereinafter described in connection with the accompanying 20 drawings, which constitute a part of this specification, and then more specifically defined in the claims at the end of the description.

In the accompanying drawings, wherein 25 similar reference characters are used to designate corresponding parts throughout the several views:

Figure 1 is a side view of a lifting and carrying device constructed substantially in 30 accordance with this invention, showing it applied to the edge of a piece of plate glass;

Fig. 2 is an outer edge view of the device as shown in Fig. 1;

Fig. 3 is an inner edge view with the glass 35 in section, and

Fig. 4 is an end view, also showing the glass plate in section.

The device comprises a pair of metal plates 1 having layers of sponge rubber 2 cemented to their inner surfaces for gripping the opposite faces of the glass 3 or other body to be carried. The plates 1 have wedges 4 cast on their outer surfaces. There are preferably four wedges on each plate, 45 and they are preferably arranged in pairs as illustrated in the drawings, the taper of each wedge being from a lower thin edge to an upper thicker edge.

A handle member 5 has spaced clamping 50 jaws 6 to embrace the plates 1 and having grooves or gutters 7 to fit over the wedges 4. Each of the jaws 6 may be made with upper and lower horizontal portions having the grooves or gutters 7 to engage the upper 55 and lower pairs of wedges 4, and vertical connecting portions 8 having vertical slots

9. The slotted parts of said connecting portions are inclined and disposed parallel to the outer surfaces of the wedges 4 on the adjacent plates 1. The plates 1 are held to 60 the handle member by lugs 10 cast on the outer surfaces of said plates, extending through the slots 9, and provided with caps 11 on the outer faces of the portions 8 of the handle member, whereby said handle member 65 may work up and down on the plates 1 for clamping and releasing the glass 3.

The hand of the carrier, when gripping the handle proper 12 of the handle member 5, is prevented from coming in contact with the edge of the glass plate by means of a rubber band or strip 13 stretched between the horizontal portions of the clamping jaws 6, said rubber strip being secured in any suitable manner, as by the screws 14. This 70 rubber strip also serves to prevent the edge of the glass from coming in contact with the metal handle member in the crotch between the clamping jaws.

In operation, when the device is applied to 80 the edge of the glass, as illustrated, the weight of said glass causes the handle member to travel upward along the wedges 4 thereby forcing the plates 1 together to firmly grip the glass between their rubber 85 lined inner surfaces. When the glass is set down, it is only necessary to give a slight tap on the upper end of the handle member to relieve the pressure thereof upon the plates 1 and release the rubber lined inner 90 surfaces of said plates from the glass.

Having thus described my invention, what I claim as new and desire to secure by Letters Patent is:

1. The combination with a pair of gripping plates having wedges on their outer faces at the upper and lower portions thereof, of a handle member having upper and lower clamping jaws provided with grooves to fit the upper and lower wedges respectively. 95

2. The combination with a pair of gripping plates having wedges on their outer faces at the upper and lower portions thereof, of a handle member having upper and lower clamping jaws provided with grooves to fit the upper and lower wedges respectively, and means of connection between said handle member and plates which allows the former to move on the latter along the wedges. 105

3. The combination with a pair of gripping plates having wedges and lugs on their 110

outer faces, of a handle member having clamping jaws to engage said wedges and slots through which said lugs are passed, there being caps on said lugs for connecting the handle member to the gripping plate while permitting the former to move on the latter along the wedges.

4. The combination with a pair of gripping plates having wedges and lugs on their outer faces, of a handle member having clamping jaws to engage said wedges and slots through which said lugs are passed, the slotted portions of said handle member being parallel to the wedges, and there being caps on the lugs for connecting the handle member to the gripping plates while permitting the former to move on the latter along the wedges.

5. The combination with a pair of gripping plates, of a handle member having an upper and a lower pair of clamping jaws embracing said plates, and a protecting strip connecting the horizontal portions of said jaws for the purpose specified.

6. The combination with a pair of gripping plates, of a handle member having an

upper and a lower pair of clamping jaws embracing said plates, and means connecting the plates to the handle member and permitting sliding movement of the latter on the former.

7. The combination with a pair of gripping plates, of a handle member having an upper and a lower pair of clamping jaws embracing said plates, sponge rubber layers on the inner faces of said plates for engaging a piece of plate glass and a rubber strip connecting the horizontal portions of the clamping jaws to prevent the edge of the glass from coming in contact with that part of the handle member.

8. The combination with a pair of gripping plates, of a handle member having spaced pairs of clamping jaws and a handle proper connecting said pairs of jaws, and a protecting strip stretched between the horizontal portions of the pairs of jaws for preventing the hand of the operator from coming in contact with the edge of an article gripped between the plates.

AUGUST DIETRICH.
